UNITED STATES PATENT OFFICE.

ROBERT MOORE, OF MONTCLAIR, NEW JERSEY.

MARKING TAPE FOR TENNIS COURTS.

Application filed November 27, 1926. Serial No. 151,092.

In United States Letters Patent No. 951,484 dated March 8, 1910, is described a marking tape or ribbon for tennis courts and the like which is composed of a thin strip 5 of metal and secured to the ground by ordinary nails driven through the strip substantially centrally of the width thereof and into the ground. Such a tape has many advantages over the theretofore known fabric 10 tape and other markers, but when it is desired to remove the tapes, for example to resurface the court, the tapes are destroyed in the operation because the nails have become corroded or rusted into the earth. 15 Therefore the nails can be pulled from the ground only with difficulty and cannot be removed from the tapes except by pulling the heads or the enlarged encrusted ends through the tape, which of course tears the 20 tape and renders it unfit for use. The nails cannot be used again, the tapes cannot be used unless the nails are removed, and the nails cannot be removed without destroying the tapes, so a set of tapes having once been 25 laid in accordance with said patented invention, which are costly, must be replaced practically every season.

One object of my invention is to provide a novel and improved marking tape of the 30 general character described which can be easily and quickly taken up or removed from a court, for example to permit reconditioning of the court, without injury to the tape or to the court, whereby the tape can 35 be used for several successive seasons.

Another object is to provide a novel and improved method of laying metal marking tapes for tennis courts and the like.

Other objects are to provide a marking 40 tape for tennis courts which may be firmly secured to the dirt surface of the court and will remain flat and immovable in all directions with no possibility of its edges curling or bending up so as to trip the player 45 or cause false bounds of the ball; to provide such a marking tape comprising a thin ribbon or strip of ductile non-elastic metal and a plurality of driven, headed, rotatable fastening members driven into the ground 50 along each edge of said ribbon in unconnected relation to said ribbon or strip but with the edges thereof clamped between the heads of said fastening members and the ground so that by rotation of said fastening 55 members or slight bending thereof outwardly from the edges of the strip, the strip may

be lifted free of the fastening; to provide a novel and improved fastening member for such a marking tape and to obtain other results and advantages as may be brought 60 out by the following description:

Referring to the accompanying drawing in which corresponding and like parts are designated throughout the several views by the same reference characters, 65

Figure 1 is a plan view of a tennis court showing the manner of marking it according to the invention and before the tapes have been rolled into the court.

Figure 2 is an enlarged fragmentary plan 70 view of one of the tapes as it appears secured to the court and before rolling;

Figure 3 is a transverse vertical sectional view taken on the line 3—3 of Figure 2 showing the tape and the fastening members 75 after they have been rolled into the ground;

Figure 4 is a perspective view of one of the fastening members, and

Figure 5 is a perspective view of a device for spacing and locating the fastening 80 members in proper relation to a tape to be secured in place.

As hereinbefore described, the marking tapes are preferably formed of narrow and thin strips or ribbons of lead, although any 85 suitable metal having the required ductility, malleability and non-elasticity may be used. The material selected for the tapes is cut into the desired lengths as designated at 1, and each tape is stretched along the line on 90 which it is to be placed, this stretching serving to take out the kinks or bends and to cause a flat even contact of the tape with the ground. The tape is then secured fast to the surface of the court. 95

In accordance with the invention the tape is so secured by means of fastening members 2 which may be driven into the ground at opposite sides of and in contact with the edges of the tape and also rotatable in the 100 ground, said fastening members having heads 3 to overlie the corresponding edges of the tape so that when the fastening members are driven in the ground the tape is clamped between said heads of the fastening 105 members and the ground. Preferably the fastening members at opposite edges of the tape are arranged in staggered or alternate relation, as shown in Figure 2 of the drawings. When the fastening members are 110 driven the heads thereof indent themselves into the upper surface of the tape as indi-

cated at 4 so as to produce a secure contact with the strip and also permit the upper surfaces of the heads of the fastening members to be located flush with or below the 5 plane of the upper surface of the strip. After the strips have been secured in position as above described and as shown by Figures 1 and 2 in the drawings, the strips are forced or partially embedded into the 10 ground, this operation being preferably performed by a roller, and the result of the operation being illustrated in Figure 3 of the drawings where the upper surface of the strips and the upper surfaces of the heads of 15 the fastening members 2 are disposed substantially in the plane of the surface of the court or ground.

Preferably the fastening members are in the nature of nails each having a straight 20 shank 5 pointed at one end as at 6 and formed at the other end with integral flat heads 7 which extend laterally at substantially right angles from one side of the shank. This form of fastening member 25 gives a maximum of contact of the head with the strip or tape 1 and eliminates all projections beyond the edges of the tape. When it is desired to remove the tapes or strips, it is merely necessary to rotate the 30 fastening members in the ground to swing the heads thereof outwardly away from the edges of the strip, as shown by dotted lines in Figures 2 of the drawings, it being then possible to simplify the strip from between the shanks of the fastening members at opposite edges of the strip. This operation is 35 particularly easy if the tapes are left in position until the ground has become soft as during thaws or in the spring when the 40 ground recedes so as to leave the nail heads considerably above the surface of the ground. In lieu of this method of removing the tape the fastening member may be bodily pulled from the ground or bent outwardly away from the strip. This in no 45 way injures the tape since the fastening members do not have any connected relation with the tape as by puncturing as in the above-mentioned Patent No. 951,484. It is 50 accordingly possible to use the tape during several successive seasons, it being only necessary to replace the fastening members which of course rust or corrode in the ground after a short time.

55 This construction has other advantages in that curling of the edges of the tape upwardly is absolutely and positively prevented and the fastening members at the edges of the tape protect said edges against being 60 torn upwardly as by a player catching his toe beneath the strips. The heads 3 of the fastening members being counter-sunk into the strip and the strip being rolled into the ground, all possibility of false bouncing of 65 the balls is eliminated as is also the possibil-

ity of the player being tripped by the strips. In fact, the fastening members in effect reinforce the edges of the strip so that such fastening members and the method underlying the use thereof not only make the 70 tapes more easily removable for reuse but at the same time make the tape more durable or long lived in use.

Of course the fastening members 2 may be spaced in position relatively to the edges 75 of the strip in any suitable manner, but I preferably use a spacing device such as illustrated in Figure 5 of the drawings and which comprises a central strip 10 of suitable material such as wood of a width substantially the same as the ribbons or tapes 80 1 and of any suitable length of several feet for convenient handling. Arranged at opposite sides of this strip are narrow fastening member holding strips 11 of the same thickness and length as the strip 10, said holding strips 11 having notches 12 at the inner edges thereof which with the adjacent sides of the strip 10 form openings to support the fastening members 2 in substantially vertical position. The notches 12 are spaced according to the desired spacing of the fastening members, and one fastening member is arranged in each of said openings. The strips 11 are separably attached to the strips 90 10 by any suitable means as illustrations of which I have shown clamping bolt 13 and a U-shaped spring clip 14. With the strip 10 and 11 assembled as shown in Fig. 5 and a fastening member in each of the openings 100 12 the device is laid upon the tape or ribbon 1 to be secured to the ground with the longitudinal edges of the strip 10 coincident to the tape 1. The fastening members are then partly driven into the ground after 105 which the strips 11 are removed from the strip 10 and the strip 10 is lifted from the tape 1 thus leaving the fastening members 2 properly spaced with respect to the tape and to be finally driven. Of course, to facilitate 110 removing of the strip 10 the fastening members will be initially placed with the heads 7 thereof extending away from the said strip, as shown in Figure 5 of the drawings, the fastening members being rotated to position with the heads over the strip or tape 115 1 before final driving.

It will be understood that the method and construction above described are presented as those now preferred by me, but obviously the method and the construction of the fastening members and the tapes may be modified or changed by those skilled in the art without departing from the scope of the invention. Therefore, I do not want to be understood as limiting myself except as required by the following claim when construed in the light of the prior art.

Having thus described the invention, what I claim is:

The combination with a tennis court having a dirt foundation, of marking tapes consisting of thin strips of ductile, malleable and non-elastic metal, and a plurality of 5 fastening members arranged in spaced relation along the edges of said strips, and said fastening members each having a shank

driven into the ground and a laterally projecting head overlying and clamping the corresponding edge of said strip between it and the ground, said head being indented 10 into the strip below the plane of the top surface thereof.

ROBERT MOORE.
